UNITED STATES PATENT OFFICE.

ALFRED O. TATE, OF NEW YORK, N. Y.

CALENDER-ROLL.

1,388,215.

Specification of Letters Patent. Patented Aug. 23, 1921.

Application filed January 29, 1921. Serial No. 440,862.

To all whom it may concern:

Be it known that I, ALFRED O. TATE, a subject of the King of Great Britain, residing in the city, county, and State of New York, have invented certain new and useful Improvements in Calender-Rolls, of which the following is a disclosure.

My invention relates to calender or Shreiner rolls such as are commonly employed for finishing cotton and other fabrics.

The objects of my invention are to construct a roll of this kind having a removable outer shell or surface which will be strong and light and which will be so constructed and arranged that the outer shell can be readily removed and interchanged, also to provide a roll of this kind with heating means so disposed as to effectively heat the surface of the roll and maintain it at an even temperature. A further object is to so construct the roll that it will maintain its cylindrical shape under heavy duty, although constructed of relatively light elements.

In the drawing accompanying and forming a part of this specification, I have illustrated the preferred embodiment of my invention. In this drawing—

Figure 1 is an end view partly in section of the complete roll.

Fig. 2 is a side elevation partly in section of the roll.

Referring in detail to the structure shown, the roll comprises the usual shaft 1, and mounted on this shaft and keyed thereto is a hub member 2, which hub member has mounted thereon a series of flat strip sections 3, which function as spokes or thrust members to support the outer wall of the roll on the hub. Inasmuch as these rolls are of considerable length, it is preferred to make these thrust members in short sections as shown in Fig. 2. The outer ends of the thrust members bear against wedge members 4, which in turn bear against and tend to hold the elongated stiffening members 5 against the inner or supporting drum or cylinder 6. The wedge members 4 are heat insulated from the stiffening members 5 by a suitable insulation 7. Each stiffening member is provided with a cavity 8 in which there is inserted an electric heater shown in the form of a coil 9. The outside cylinder 10 which for some operations is formed with special surfaces is removable and may readily be removed when the face plate 11 is

detached. In this connection, attention is called to the fact that the spokes or thrust members 3 are tangentially disposed with respect to the hub. That is to say that each spoke is disposed at a slight angle to the radial line extending from the center of the hub to the spoke and the spokes are inclined at their outer ends in the direction of rotation. This arrangement of the spokes is an advantage in that when the roll is rotated in service in the direction indicated by the feathered arrow in Fig. 1, the spokes tend to assume the position of radial lines and thrust the members 5 outwardly against the inside wall of drum 6 and thus hold the surface of the roll 10 against its work. The outward thrust of the spokes also operates to maintain the roll a true cylinder. In this way, I find that a very satisfactory construction is obtained with a minimum of material. Moreover, when the roll is idle, the spokes assume the tangential position and allow the supporting cylinder 6 to contract sufficiently to allow the outer cylinder 8 to be readily withdrawn and replaced. It will be noted that a pin 12 on the opposite end of each of the wedges is arranged to move in a short slot 13 cut in the end plates 11. These slots allow the spokes to move from their normal tangential position into radial position but do not allow them to go beyond this radial position.

I am aware that various modifications may be made and I desire protection as to all such modifications as come within the scope of my claims.

What I claim as my invention is:

1. A roll of the kind described comprising a hub member, a removable calender cylinder, means for supporting the cylinder on the hub comprising a series of compression spokes extending outwardly from the hub, each spoke being disposed at a slight angle to a line extending from the center of the hub outwardly to the spoke.

2. A roll of the kind described comprising a hub member, an outer removable cylinder, means for supporting the cylinder on the hub comprising a series of compression spokes extending outwardly from the hub, each spoke being disposed at a slight angle to a radial line extending from the center of the hub to the spoke, the inclination of the spokes being such that they tend to assume radial positions when the drum is rotated in service.

3. A roll of the kind described comprising an outer removable cylinder, an inner cylinder, an interior back or support for the inner cylinder comprising elongated stiffening members triangular in cross section, wedge members disposed between and adapted to force the stiffening members apart, a hub and thrust members extending from the hub to the wedges. 30
- 5 4. A roll of the kind described comprising an outer removable cylinder, an inner cylinder, an interior back or support for the inner cylinder comprising elongated stiffening members triangular in cross sections, 35
- 10 wedge members disposed between and adapted to force the stiffening members apart, a hub and thrust members extending from the hub to the wedges, the thrust members being inclined at their outer ends in the direction of rotation. 40
- 15 5. A roll of the kind described comprising an outer removable cylinder, an inner supporting cylinder, elongated stiffening members disposed on the inside of the supporting cylinder, means for supplying heat 45
- 20 to the interior of said stiffening members, 50
- 25 wedge members so disposed as to hold the stiffening members apart and in contact with the supporting cylinder and means for forcing the wedges into position. 30
- 30 6. A roll of the kind described, comprising a cylinder, segmental longitudinal stiffening members for said cylinder, heating means inclosed within said stiffening members, wedge members so disposed as to hold 35
- 35 the stiffening members apart and in contact with the supporting cylinder, means for forcing the wedges against the stiffening members and heat insulating means between said wedges and said stiffening members. 40
- 40 7. A roll of the kind described comprising a cylinder, a hub for said cylinder, segmental longitudinal stiffening members for said cylinder, wedging members for forcing said stiffening members against said cylinder, 45
- 45 said wedging members having projecting pins at their ends, means for forcing said wedging members against said stiffening members, and an apertured plate engaging said pins for limitng the movement of said 50 wedging members.

ALFRED O. TATE.
